UNITED STATES PATENT OFFICE.

JOHN A. JOSSELYN, OF NATICK, MASSACHUSETTS, ASSIGNOR OF ONE-FOURTH TO ALFRED F. SEYMOUR AND ONE-FOURTH TO GRACE M. TIBBETTS, BOTH OF CAMPELLO, MASSACHUSETTS.

HEEL-BUILDING MACHINE.

No. 915,356.

Specification of Letters Patent. Patented March 16, 1909.

Application filed November 25, 1907. Serial No. 403,579.

To all whom it may concern:

Be it known that I, JOHN A. JOSSELYN, a citizen of the United States, residing at Natick, in the county of Middlesex and State 5 of Massachusetts, have invented new and useful Improvements in Heel-Building Machines, of which the following is a specification.

This invention relates to a machine for 10 building and forming the heels of boots and shoes.

The heels to be built and formed on the machine of this invention are first built up by hand from a series of lifts which are joined 15 together by paste. The heel while in this condition is placed in a form, which form is expandable laterally thereof, and the heel is then submitted to lateral compression in the form and also to compression against the bottom lift thereof, whereby the same is molded 20 in the form and the different lifts are securely and closely pressed together. Subsequently to the forming operation the heel is shaved by a suitable knife and then gouged 25 on the bottom lift thereof. Finally the heel is ejected from the machine, all of these different operations being performed automatically, while the carrier for the heel, upon which the form is located, returns to have 30 another heel built in the form located on said carrier, after said operations are completed.

The invention consists in the combination and arrangement of parts set forth in the following specification and particularly pointed 35 out in the claims thereof.

Referring to the drawings: Figure 1 is a plan view of my improved heel building machine, a portion thereof being broken away to save space in the drawings. Fig. 2 is a side elevation of the same. Fig. 3 is a sectional elevation taken on line 3—3 of Fig. 1. Fig. 4 is a detail section taken on line 4—4 of Fig. 1 as viewed from the front of the machine. Fig. 5 is a sectional elevation broken away to 45 save space taken on line 5—5—5, Fig. 1. Fig. 6 is a sectional elevation taken on line 6—6 of Fig. 1. Fig. 7 is a perspective view of the completed heel.

Like numerals refer to like parts through 50 out the several views of the drawings.

In the drawings, 10 is the frame of the machine provided with ways 11 extending longitudinally thereof and adapted to receive and guide a carrier slide 12 upon which is located 55 an expandible form 13 adapted to receive the

heel which is to be operated upon, as hereinbefore set forth. The expandible form 13 consists of two parts, viz., the part 14 fastened by screws 15 to the carrier slide 12 and a movable part 16 which is adapted to be moved laterally upon the slide 12 and is guided by screws 17 which project through slots 18 in the movable part 16 and extend into the slide 12. Springs 18 inserted in holes in the parts 14 and 16 tend to move the part 16 toward the right (Fig. 1) or to expand the form. The operator places the heel in a recess 19, about one-half of which is formed in the movable part 16 and the other half in the fixed part 14 of the expandible form. The movable part 16 is moved toward the fixed part 14 against the action of the springs 18 by means of a lever 20 which is pivoted at 21 to a bracket 22 fast to the slide 12. Said lever extends forwardly from its pivoted end and its free end 75 is wedge-shaped in cross section (see Fig. 4) and bears against the inclined outer edge of the movable part 16.

The outer edge of the lever 20 bears against guide pins 23 and it will be evident that 80 when the lever 20 is forced downwardly, as hereinbefore described, the front end thereof, which constitutes a wedge, will force the movable part 16 of the form toward the left, thus contracting said form and submitting the heel contained therein to lateral compression. The downward movement of the lever 20, hereinbefore referred to, is accomplished by means of a slide 24 which bears at its lower end against the upper edge 90 of the lever 20 and at its upper end bears against a cam 25 which is fastened to a shaft 26 extending transversely of the machine and journaled to rotate in bearings 27, 27 upon the frame 10. A spring 28 moves the 95 slide 24 upwardly and holds the same in contact with the periphery of the cam 25. The shaft 26 is driven by a pulley 29 which is loose upon said shaft, but is adapted to be fastened thereto by means of a clutch 30 100 operated by a clutch slide 31 which is held normally in its upward position by means of a spring 32 and is moved downwardly to release the clutch and allow it to connect the pulley 29 to the shaft 26 by a lever 33, Fig. 2 105 pivoted at 34 to the frame of the machine, the vertical arm of said lever being in alignment with an arm 35 fast to a collar 36 which, in turn, is fastened to a shaft 37. The shaft 37 is journaled to rotate in suitable 110

bearings upon the frame of the machine and has a worm gear 38 fast thereto and meshing into a worm 39 which is rigidly fastened to the clutch shaft 40. The clutch shaft 40 is 5 journaled to rotate in bearings 41, 41 upon the frame of the machine and has two pulleys 42 and 43 loosely mounted thereon. The pulley 43 is rotated by a straight belt 44 extending therefrom to a pulley 45 fast 10 to the main driving shaft 46, which is journaled to rotate in bearings 47 upon the frame 10. The driving shaft 46 is rotated by a pulley 48 fast thereto and has a worm 49 fast thereto which meshes into a worm 15 gear 50 formed upon the end of a hub 51 fast to the pulley 29. The pulley 42 is connected by a cross-belt 52 to a pulley 53 fast to the shaft 46. An intermittent recipro- 20 catory motion is imparted to the carrier 15 slide 12 by an intermittent gear 54 which is fastened to the shaft 37 and has teeth ex- tending partly therearound. Said gear 54 meshes into a rack 55 which is fastened to the carrier slide 12, Fig. 3.

25 Compression is given to the heel in a direction at right angles to the tread thereof by a plunger 56 (Fig. 3) formed of a lower part 57 and an upper part 58 adapted to slide one within the other. A pin 59 fast 30 to the part 57 projects through a slot 60 in the part 58, while a spring 61 located in a recess 62 within the part 58 bears at its upper end against the part 58 and at its lower end against the upper end of the part 57, thus 35 tending to keep said parts in the position illustrated in Fig. 3. The upper end of the part 58 is connected by a connection 63 to a crank 64 upon the shaft 26. The lower end of the connection 63 has a ball 63' adjustably 40 secured thereto which fits in a socket 58' in the upper end of the part 58, so that the plunger 56 is connected by said ball-joint connection or by a universal joint connec- 45 tion to the crank 64.

50 A pressor roll 65 (Fig. 3) formed preferably of yielding material, such as rubber, is fastened to a shaft 66 journaled to rotate in a bracket 67 which is adjustably fastened by a screw 68 to a cross-head 69 rigidly secured 55 to the frame of the machine. The roll 65 is placed in proper position to bear against the bottom lift of the heel as the same is fed through the machine, as hereinafter de- 60 scribed, and adjacent to said roll is a sta- tionary knife 70 which is adapted to shave the bottom lift of the heel after it passes the roll 65. Said stationary knife is fastened to a cross-beam 71 which, in turn, is fastened to the frame of the machine.

65 A rotary cutter 72 for gouging the bottom lift of the heel after it has been shaved by the stationary knife is fastened to a shaft 73 which is journaled to rotate in a bearing 74 formed in the lower end of a slide 75 which 70 is adapted to slide vertically in the frame of

the machine and is forced downwardly by a spring 76 which encircles a stem 77 extending upwardly from the slide 75 and through a plate 78 fast to the frame of the machine.

A lever 79 (Fig. 2) is pivoted at 80 to the frame of the machine and is connected by a screw 81 to the slide 75. The free end of the lever 79 has a roll 82 journaled thereon and in alignment with a cam block 83 fast to the carrier slide 12, so that when said carrier 75 slide is moved backwardly, as hereinafter de- scribed, at a certain time in the rotation of the machine, the cam 83 encounters the roll 82, lifts the lever 79 and thus moves the slide 75, together with the rotary cutter 72, up- 80 wardly so that the gouge in the bottom lift of the heel will gradually decrease in depth from the breast of said heel toward the rear portion thereof.

The heel is ejected from the form by an 85 ejector 84 which is adapted to slide vertically in the carrier slide 12 and has journaled thereon at its lower end a friction roll 85, which, as the carrier slide 12 is moved back- 90 wardly, engages a stationary cam block 86 95 which forces the ejector upwardly and thus forces the heel out of the form 13. A U- shaped spring ejector finger 87 engages the heel upon the return movement of the car- 100 rier slide and pushes the same off of the slide 95 down the inclined plate 88 upon the back of said slide and into a convenient receptacle therefor located at the rear of the machine.

It is necessary that the slide which carries 105 the heel which is to be compressed, shaved, gouged and ejected from the machine shall first move backwardly from the operator to, the mechanism which compresses the heel at right angles to the tread thereof and then stop while said compression is taking place. 110 After the compression has taken place the slide again moves backwardly until the heel passes the shaving and gouging cutters to the extreme rear portion of the machine and until the heel is ejected from the form. 115 Then the carrier slide moves forward again to its extreme forward position and stops so that the operator can place another heel in the form. To encompass these different motions a reversing clutch mechanism is pro- 120 vided which I will now proceed to describe.

Referring to Fig. 2 it will be seen that when the parts are in the position illustrated in said figure—that is, with the carrier slide 12 forward and the machine stationary in readi- 125 ness for the operator to place a heel in the ex- pansible form, both of the clutches 90 and 91 are out of engagement with their respective pulleys 42 and 43. It will be understood that the clutches 90 and 91 are slidable longi- 130 tudinally of the shaft 40 and are splined thereto and that the pulleys 42 and 43 are loosely mounted upon the shaft 40. An arm 92 projects into an annular groove 93 in the clutch sleeve 90 and is fastened at its upper

end to a slide 94 which is adapted to slide upon the frame of the machine and is guided by screws 95, 95 fast to said frame and projecting through slots 96, 96 in said slide 94. 5 The left hand end of said slide rests in a notch 97 formed in the upper end of a slide 98 which is connected at its lower end to a treadle 99 pivoted at 100 to the frame of the machine. A spring 101 tends to move the 10 slide 94 toward the left (Fig. 2) or toward the front of the machine. An arm 102 fast to the slide 94 is arranged in alinement with a stop lever 103 pivoted at 104 to the frame of the machine and having its forward end connected to a spring 105 while its rearward end 15 106 projects downwardly behind a slide 107 which is arranged to slide upon the frame of the machine and is guided by screws 108, 108 which project through slots 109, 109 in said 20 slide. A spring 110 tends to move the slide 107 toward the right (Fig. 2) or toward the rear of the machine. The slide 94 has a right angled plate 111 fast to the under side thereof and adapted to be engaged by a pin 25 112 fast to the collar 36. The slide 107 has a right angled plate 113 fast to the under side thereof and adapted to be engaged by a pin 114 fast to the collar 36. An arm 115 is fastened to the slide 107 and projects downwardly, the lower end thereof projecting into 30 an annular groove 116 provided in the clutch sleeve 91.

The general operation of the machine hereinbefore specifically described is as follows:

35 Assuming the parts to be in the position illustrated in Figs. 1, 2 and 3, the operator places the heel 117, formed of lifts pasted together, in the recess 19 in the expansible form 13 and depresses the treadle 99, thus moving the 40 slide 98 downwardly until the upper end thereof clears the slide 94 and allows the same to be moved forwardly by the spring 101. As the slide 94 is thus moved forwardly, by means of the arm 92 it moves the clutch 45 sleeve 90 into engagement with the clutch pulley 42 and thus causes the shaft 40 to be rotated by said pulley in the direction of the arrow *a* (Fig. 2). This rotates the worm 39, which rotates the worm pinion 38 and intermittent gear 54 in the direction of the arrow *b* (Fig. 2). The rotation of the intermittent gear 54 in the direction of the arrow *b* moves the rack 55 and carrier slide 12, together with the expansible form 13 and lever 20, toward 50 the right or toward the back of the machine until the heel is brought into alinement with and underneath the plunger 56. At this time the toothed portion of the gear 54 passes out of mesh with the rack 55, thus leaving 55 said rack stationary, together with the gear and the parts connected thereto. During this backward movement of the rack and before the plunger compresses the heel the arm 35 upon the collar 36 engages the lower 60 end of the vertical arm of the lever 33 and

rocks said lever so that the horizontal arm thereof moves downwardly, and as said horizontal arm is in engagement with the pin 31', fast to the clutch slide 31, said clutch slide will be moved downwardly, thus releasing 70 the clutch 30 which will then engage the pulley 29 and cause the shaft 26 to be rotated, it being understood that the clutch pulley 29 is rotated continuously through the shaft 46, worm 49 and worm gear 50. 75

The rotation of the shaft 26 causes the cam 25 to be rotated and the slide 24 to be moved downwardly, engaging the lever 20 and forcing the same downwardly, so that the inclined inner edge of said lever engaging the 80 inclined outer edge of the movable part 16 forces said movable part toward the heel and compresses the same laterally thereof against the fixed portion 14 of the form. As soon as the carrier slide has come to a stop, the shaft 85 26 being rotated as hereinbefore described moves the plunger 56 downwardly by means of the crank 64 and connection 63 until the lower portion of said plunger 56 bears against the bottom lift of the heel, compressing the 90 same in the form. The under surface of the lower part 57 will adapt itself to bear against the bottom lift of the heel over its entire surface, whether said bottom lift be exactly parallel to the under face of the part 57 or not by 95 reason of the ball joint 65 which allows the plunger to swing, it being understood that the same fits loosely in its guide-ways.

Having performed the compressing operation—that is, as to the vertical compression 100 of the heel and retreated to its uppermost position as illustrated in Fig. 3, the arm 35 passes beyond the lever 33 and releases the same, whereupon the spring 32 moves the clutch slide 31 upwardly, engaging the clutch 105 30 to release the same from the clutch pulley 29, so that said clutch pulley is then free to rotate without rotating the shaft 26 and said shaft 26 becomes stationary. The slide 24 will also move upwardly into its uppermost 110 position, being thus moved by the spring 28, as illustrated in Fig. 5. The lever 20, however, being wedged downwardly as hereinbefore described between the guide-pins 23 and the movable part of the expansible form, will 115 remain in this position and the lateral compression of the heel will continue until after the heel has passed the stationary knife 70 and the rotary cutter or gouging cutter and just before the heel is ejected from the form, 120 whereupon a laterally projecting pin 118 will engage the inclined edge 119, Fig. 3, of a block 120 fast to the frame of the machine, when, upon the continued movement of the carrier slide, to which said lever is pivoted, 125 the lever 20 will be forced upwardly, thus releasing the movable portion of the expansible form. Said movable portion is then forced away from the fixed portion by the springs 18, 18. After the plunger has been raised 130

sufficiently to release the vertical compression upon the heel the gear 54 again meshes into the rack 55 and moves the carrier slide farther toward the rear of the machine until 5 the bottom lift of the heel 117 is brought beneath the yielding roll 65 and subsequently into engagement with the stationary knife 70. At this time the bottom lift is shaved and as the heel is subsequently carried by the 10 carrier slide toward the rear of the machine, said heel is gouged at 121 by the rotary cutter 72. The gouge 121 is for the purpose of enabling the heel to fit the rounded portion of the shank of the shoe sole, and thus renders 15 the completed heel independent of the compressing machine which is ordinarily used for this purpose.

In order to cause the gouge to decrease in depth from the breast toward the rear of the 20 heel, as shown in Fig. 7, the rotary cutter 72 is moved upwardly by reason of the cam block 83 coming into contact with the roll 82, which moves the lever 79 upwardly and thus lifts the rotary cutter gradually until it 25 clears the heel. After having been thus compressed, shaved and gouged the form releases the heel from side pressure, as hereinbefore described, and the heel is ejected by the ejector 84 which rides upwardly on 30 the cam block 86 and pushes the heel out of the form and up between the two side arms of the U-shaped spring ejector 87. The parts are now in position to have the slide reverse its movement and move forward, 35 whereupon the cross-bar of the ejector finger 87 will engage the heel and push the same off of the slide, said heel sliding downwardly over the curved inclined plate 88 and into a suitable receptacle, while the slide 40 passes forward to the front of the machine and stops to have a new heel placed therein by the operator. In order to accomplish this reversing movement the pin 112, which is fastened to the collar 36, is so placed relatively to the other parts as to, at this time, 45 engage the right angled plate 111 and move the same toward the right (Fig. 2), and the slide 94 will also be moved to the right, moving the downwardly projecting arm 92 and 50 the clutch sleeve 90 toward the right and out of engagement with the clutch pulley 42. The slide 98 is then moved upwardly by the treadle 99 and by the spring 122 which is fastened to said treadle. The left 55 hand end of the slide 94 thus projects into the notch 97 in the upper end of said slide 98 and will remain in this position until said slide is depressed by the operator, as hereinbefore described, upon the commencement of a new cycle of operations of the 60 mechanism hereinbefore described.

When the slide 94 is moved toward the right, as hereinbefore described, the extended arm 102 fast thereto will engage at its 65 right hand end (Fig. 2) the left hand end of

the lever 103 and tipping the same upon its pivot 104 will raise the end 106 of said lever and disengage the slide 107 therefrom, which will then be moved toward the right by the spring 110, thus moving the arm 115 and the 70 clutch sleeve 91 which it engages toward the right until said clutch sleeve engages the pulley 43, which, it will be remembered, rotates in the opposite direction to that in which the pulley 42 rotates. Thus the shaft 75 40 will be rotated by the pulley 43 in the direction opposite to the arrow *a* and the intermittent gear 54 will be rotated in the direction opposite to the arrow *b*, thus moving the slide 12 toward the front of the machine 80 until it is stopped by the pin 114 engaging the angle plate 113 and moving the slide 107 toward the left (Fig. 2), thus moving the clutch sleeve 91, through the downwardly projecting arm 115 toward the left and disengaging said clutch sleeve from the pulley 43, whereupon the shaft 40 becomes stationary and the several parts are then in the position illustrated in Fig. 2.

It has been found to be very advantageous in a machine of the character hereinbefore described to use a flexible material, such as rubber, for the presser roll 65, for the reason that the same bears against the leather of the heel and is flattened at that 90 portion thereof which bears against said heel, so that instead of bearing along a line extending longitudinally thereof, as would be the case in a roll formed of brass or hard material, said roll, when formed of rubber, 100 will bear along the flattened portion of its periphery against the leather of the heel and such flattened portion will hold the heel firmly in position in the form and close to the edge of the stationary knife 70, so that 105 the shaving will be done without any vibration or chattering of the heel in the form.

As hereinbefore set forth the heel is compressed laterally during the first part of the reciprocatory motion of the carrier slide and 110 is held compressed while the slide is subsequently in a stationary position, and while said heel is being subjected to compression vertically or upon the bottom lift thereof, said heel is also held under lateral compression during the further forward movement of the slide and while the heel is being shaved and gouged. There are several advantages in thus subjecting the heel to lateral compression in the manner and during the time 115 set forth.

First, more satisfactory results are obtained by compressing the heel laterally prior to the vertical compression thereof or the compression at right angles to the bottom 125 lift of the heel.

Second, holding the heel under lateral compression in the form during the shaving and gouging operations makes much more satisfactory work, for the reason that the 130

heel is firmly held and cannot chatter during the time when the shaving and gouging operations are taking place; and

Third, the heel is held under lateral compression during the entire time taken by all of the other operations to which it is subjected except the time taken to eject the heel from the machine, and it is well known to those skilled in the art that the longer a heel is subjected to pressure the better and more lasting will be the results desired. In a quick running machine the difference between subjecting the heel to lateral compression at one point in the movement of the slide and subjecting said heel to lateral compression during the entire forward movement of the heel would be the same as subjecting said heel to a sudden blow or to a long continued pressure.

Having thus described my invention, what I claim and desire by Letters Patent to secure is:

1. In a heel building machine, a carrier slide, mechanism to impart a reciprocatory motion to said slide, a form on said slide adapted to receive a heel, said form made in two parts, one movable relatively to the other, a lever pivoted to said slide adapted to bear against said movable part and constructed to move said movable part, means to rock said lever to move said movable part toward the other part of said form to compress said heel laterally thereof during the first part of the forward motion of said slide, said lever adapted to hold said movable part stationary relatively to said other part, with said heel under compression during a further forward motion of said slide, and other means adapted to rock said lever to allow said movable part to be moved away from the other part of said form during the latter part of the forward movement of said slide.

2. In a heel building machine, a carrier slide, mechanism to impart a reciprocatory motion to said slide, a form on said slide adapted to receive a heel, said form made in two parts, one movable relatively to the other, means adapted to move said movable part toward the other part of said form to compress said heel laterally thereof during the first part of the forward motion of said slide, said means adapted to hold said heel under lateral compression during a further forward motion of said slide, a knife adapted to shave the bottom lift of said heel, and a cutter adapted to gouge said heel from the breast toward the back thereof while said heel is subjected to lateral compression.

3. In a heel building machine, a carrier slide, mechanism to impart a reciprocatory motion to said slide, a form on said slide adapted to receive a heel, said form made in two parts, one movable relatively to the

other, means adapted to move said movable part toward the other part of said form to compress said heel laterally thereof during the first part of the forward motion of said slide, said means adapted to hold said heel under lateral compression during a further forward motion of said slide, a knife adapted to shave the bottom lift of said heel, a cutter adapted to gouge said heel from the breast toward the back thereof while said heel is subjected to lateral compression, and instrumentalities adapted to move said cutter toward and away from said heel.

4. In a heel building machine, a carrier slide, mechanism to impart a reciprocatory motion to said slide, a form on said slide adapted to receive a heel, said form made in two parts, one movable relatively to the other, means adapted to move said movable part toward the other part of said form to compress said heel laterally thereof during the first part of the forward motion of said slide, said means adapted to hold said heel under lateral compression during a further forward motion of said slide, a knife adapted to shave the bottom lift of said heel, a cutter adapted to gouge said heel from the breast toward the back thereof while said heel is subjected to lateral compression, as set forth, means to release said lateral compressing means, and means to eject said heel from said form.

5. In a heel building machine, a carrier slide, mechanism to impart a reciprocatory motion to said slide, a form on said slide adapted to receive a heel, said form made in two parts, one movable relatively to the other, means adapted to move said movable part toward the other part of said form to compress said heel laterally thereof during the first part of the forward motion of said slide, said means adapted to hold said heel under lateral compression during a further forward motion of said slide, a compressor, mechanism adapted to press said compressor against the bottom lift of said heel while said slide is stationary and after said heel has been compressed laterally, said mechanism adapted to move said compressor away from said heel prior to said further forward motion of the same, a knife adapted to shave the bottom lift of said heel, and a cutter adapted to gouge said heel from the breast toward the back thereof while said heel is subjected to lateral compression, as set forth.

In testimony whereof I have hereunto set my hand in presence of two subscribing witnesses.

JOHN A. JOSSELYN.
